UNITED STATES PATENT OFFICE.

JASON W. COOPER, OF ST. PAUL, MINNESOTA.

DESIGN FOR WRAPPING-PAPER.

SPECIFICATION forming part of Design No. 35,673, dated February 4, 1902.

Application filed October 7, 1901. Serial No. 77,921. Term of patent 14 years.

To all whom it may concern:

Be it known that I, JASON W. COOPER, a citizen of the United States, and a resident of St. Paul, in the county of Ramsey and State 5 of Minnesota, have invented and produced a new and original Design for Wrapping-Paper, of which the following is a specification.

The accompanying drawing represents a portion of the paper ornamented with the design forming the subject-matter of my invention.

As shown in said drawing, the essential or material feature of my design consists in the representation of a series of dwelling-houses 15 of like design arranged upon the paper at

widely-diversified angles, so that the angular spaces formed by the irregular outlines of the houses are largely filled, so as to give a uniform ornamental appearance to the paper as a whole. 20

Having thus described my new design, I declare that what I claim as new therein, and desire to secure by Letters Patent, is—

The design for wrapping-paper, substantially as herein shown and described.

JASON W. COOPER.

In presence of—

C. R. WENZEL,
A. WILKINSON.
